SELF-BRAKING WINCH DRIVE

Beatty M. Crawford, Santa Ana, Calif.

Application March 13, 1944, Serial No. 526,289

3 Claims. (Cl. 192—4)

This invention relates to a self-braking winch drive and like constructions.

The invention has been primarily designed for use in conjunction with a power mast and boom hoist such as is disclosed in my co-pending application Serial No. 495,185 filed July 17, 1943, although it may be used in conjunction with other similar constructions.

In various types of constructions it is desirable to provide a drive whereby a winch or other driven element may be power driven or forcibly rotated in either direction and upon disconnecting the driving connection between the winch and the source of power to immediately and automatically brake the winch to hold it against continued rotation in either direction. A device of this character is highly desirable on hoists of various kinds where the load may be raised or lowered by means of a winch and on disconnecting the driving connection between the source of power and the winch the winch will be held against continued rotation so that the load will not be dropped but will be maintained in the position where it was at the time that the driving connection was broken.

Another object of the invention is to provide a simple, sturdy and economical construction enabling the above mentioned functions to be easily and smoothly performed, wherein there are relatively few moving parts, all of which are so designed that they cannot readily get out of order or require repair or replacement.

With the foregoing and other objects in view which will be made manifest in the following detail description and specifically pointed out in the appended claims, reference is had to the accompanying drawings for an illustrative embodiment of the invention, wherein,

Fig. 1 is a partial view of a truck body illustrating a power mast and boom hoist such as is disclosed in my co-pending application, mounted thereon and illustrating the mechanism embodying the present invention as having been applied thereto.

Fig. 2 is a top plan view of a portion of the truck chassis illustrated in Fig. 1, the parts being illustrated in horizontal section. This view may be regarded as having been taken substantially upon the line 2—2 upon Fig. 1.

Fig. 3 is a vertical section through the lower portion of the mast of the hoist disclosed in my co-pending application and illustrating parts of the drive mechanism embodying the present invention as having been associated therewith.

Fig. 4 is a partial view illustrating the position assumed by the mechanism in providing a driv-

ing connection between the source of power and the winch.

Fig. 5 is a view similar to Fig. 4 but illustrating the position assumed by the parts when in braking position.

Referring to the accompanying drawings where-in similar reference characters designate similar parts throughout, 10 indicates a truck body on which is mounted a suitable hoist, the mast of which is indicated generally at 11 and the boom of which is indicated generally at 12. The mast is made up of telescopic sections so that it may be raised and lowered and some of these sections are adapted to be rotated such as by a worm 13 mounted on a shaft 14 so as to swing the boom 12 about a vertical axis through the mast. On the boom there is illustrated a trolley 15 a part of which can be lowered from the end of the boom as is disclosed in my co-pending application. A cable 16 extends upwardly through the mast and serves to not only raise and lower sections of the mast 11 but to raise and lower that portion of the trolley which is suspended from the boom. It also serves to draw the trolley inwardly along the length of the boom. Cable 16 is attached to and is adapted to be wound up on a winch 17 and unwound therefrom.

Shaft 18 which constitutes the source of the power for the drive embodying the present invention is driven by a power take-off at the transmission of the truck. It may be rotated, however, by any other suitable source of power and is adapted to be rotated when operating continuously in the same direction. On this shaft there are two opposed spaced disks 19 and 20, each of which is engageable by friction disks or driven disks 21 and 22 disposed therebetween. Disk 21 is mounted on a shaft 23 which is connected by gearing 24 to the winch 17. Disk 22 is mounted on shaft 25 which is connected by gearing 26 to shaft 14 on which worm 13 is mounted. The shafts 23 and 25 are mounted on standards 26 which are equipped at their lower ends with feet 27 that terminate at their ends in toes 28 and 29. Spring actuated bolts 30 extend through the feet and through a suitable supporting structure 31 urging the feet downwardly so that the disks 21 and 22 are normally urged into positions wherein they are in peripheral engagement with the supporting structure 31 that constitutes or thus affords a braking surface. The upper ends of the standards 26 are slidable in grooves 32. The standards 26 have operating rods 33 and 34 connected thereto and these operating rods are in turn connected to operating levers 35 that are

suitably located, such as adjacent the rear of the truck body as shown on Fig. 1.

The operation and advantages of the above described construction are as follows: Whenever it is desired to wind up cable 16 on the winch or drum 17, operating lever 35 which operates the standard 26 on which disk 21 is mounted, may be forced forwardly. This causes the upper end of standard 26 that supports disk 21 to slide forwardly in groove 32, the standard rocking or tilting on toe 29. The periphery of disk 21 is thus lifted out of engagement with supporting structure 31 and is brought into engagement with driving disk 20 whereby a frictional drive is established between shaft 18 and the drum 17. When cable 16 has been wound up on the drum the desired distance, operating lever 35 may be released. This permits the spring actuated bolts 30 to become effective to return the standard 26 to its normal neutral position. In this position disk 21 has disengaged disk 20 and has been caused to re-engage supporting structure 31. The disk 21 is thus peripherally held against continued rotation and automatically locks the drum 17 against continued rotation and against unwinding of the cable 16 therefrom. Conversely when operating lever 35 is pulled rearwardly standard 26 is caused to have its upper end slide rearwardly through groove 32 and will rock about toe 28 as a center. Disk 21 is thus caused to disengage structure 31 and to frictionally engage disk 19 whereby winch or drum 17 is reversely rotated so as to unwind cable 16 therefrom. Release of lever 35 causes the spring actuated bolts 30 to again become effective to return the parts to normal or neutral position, wherein disk 21 is frictionally held or braked against further rotation and consequently drum 17 is automatically locked.

In a similar manner, disk 22 may be caused to optionally engage either disk 20 or disk 19 to rotate shaft 14 in either direction. Whenever its operating lever 35 is released, disk 22 will be automatically caused to re-engage supporting structure 31 and thus lock shaft 14 against continued rotation.

From the above described construction it will be appreciated that a self-braking winch drive has been provided which is of very simple and durable construction. The driven shaft whether it be 23 or 14 can be optionally driven in either direction by the source of power which rotates shaft 18. Whenever the operating lever that is

used to establish the driving connection between the disks is released, the driven disk 21 or 22 as the case may be is instantly and automatically returned to braking position wherein it can no longer rotate. In this manner control of the hoist is maintained at all times.

Various changes may be made in the details of construction without departing from the spirit or scope of the invention as defined by the appended claims.

I claim:

1. A device of the class described, comprising a pair of spaced drive disks, a driven disk between the drive disks adapted to be optionally brought into frictional engagement with either of the drive disks so as to be driven thereby in either direction, braking means also engageable by the driven disk, and means normally urging the driven disk into engagement with the braking means so that when the driven disk is released from engagement with one of the drive disks it will be automatically braked.

2. A device of the class described comprising a pair of spaced drive disks, a driven disk between the drive disks adapted to be optionally brought into frictional engagement with either of the drive disks so as to be driven thereby in either direction, a standard supporting the driven disk, said standard having a foot thereon terminating at its ends in toes, means yieldably urging the standard into a position wherein the driven disk is out of engagement with the drive disks, means serving to brake the driven disk and into engagement with which the driven disk is urged by said means, and means for tilting the standard about either of said toes.

3. A device of the class described comprising a pair of spaced drive disks, a driven disc between the drive discs adapted to be optionally brought into frictional engagement with either of the drive discs so as to be driven thereby in either direction, a standard supporting the driven disc, said standard being tiltable about either of two spaced points to bring the driven disc into engagement with either of the drive discs, means yieldably urging the standard into a position wherein the driven disc is out of engagement with the drive discs, means serving to brake the driven disc and into engagement with which the driven disc is urged by said means, and means for tilting the standard.

BEATTY M. CRAWFORD.
